Sallets Patent

June 14, 1834.

The Schedule referred to in these Sallets Patent and making part of the same containing a description in the words of the said R. G. M. Birney himself of his Improvement in the mode of constituting springs to railroad cars

To all whom it may concern. Be it known that I, R. G. Birney, of the city of Baltimore in the State of Maryland, Civil Engineer, have invented a new and useful improvement in the mode of constituting springs for railroad cars and that the following is a full and exact description thereof, reference being had to the accompanying drawings, which make a part of this Specification. The more perfectly to set forth the nature of my improvement I will first briefly describe the construction of those springs, which have been most generally used for railroad cars both in this country and in England. Fig. 1. represents a plate of cast or wrought iron which is bolted onto the outside of the side rail of a car and sometimes on both sides of each side rail, a pair of such plates being occasionally used. The parallel sides of these plates serve as guides to the eye B, which receives the axle and allows it to follow the motion of the spring and at the same time checks its tendency to lateral or longitudinal deviation. The spring is placed above the eye in the manner shown in the drawing, it rests bearing upon plates on the under part of the side rail. These springs are generally made from 30 to 35 inches in length, from 2 $\frac{1}{2}$ to 3 $\frac{1}{2}$ inches deep in the center the plates being from 3 to 3 $\frac{1}{2}$ inches broad. Fig. 2. is a cast or wrought iron frame bolted on to the lower side of the rail of the car. The eye of the axle sliding in it as in the former case the spring C is placed above the rail its ends being attached to links D D, by means of bolts passing through them and through eyes formed in the ends of the springs C so as to prevent its bending round. A vertical bolt E extends from the upper side of the eye of the axle to the lower side of the spring. Other springs do not differ from the former in their general dimensions. The great expense of springs so constructed has induced the invention of other places for mounting them by which it was hoped the interest of cost would be

R. G. B.

produced at a diminished cost. One kind of these springs is shown at fig 3. These have been usually made about 24 inches long 2 $\frac{1}{4}$ inches deep and about 2 $\frac{1}{4}$ broad scrolled or bent round at one or both ends the scrolls being attached by bolts to iron castings A. &. bolted on to the underside of the side rail. When one end only is scrolled the other slides in a mortise or slot in one of the castings, the bearing box for the axle is bolted on to the lower side of the spring. To these springs the following practical objections exist the scroll or scrolls on these ends tend to diminish their elasticity and they do not sufficiently resist the effect of lateral movement or thrust, but are liable to become loosened or disengaged. That represented in fig 4. resembles the one last described as will be seen by inspection. the bearing box however is bolted on to the upper side of the spring and is held in its place by means of an iron strip or strap which passes over it. this without obviating the objections to the one last named, causes the car to be hung inconveniently low. The object which I profess to have attained is the furnishing a spring which shall answer all the purposes of those just described but from their greater simplicity they shall be much less expensive, and be at the same time free from the objections which exist against the two latter kinds. The spring as I construct it is shown at figure 5 and and in its general appearance bears a resemblance to that of fig. 3. but differs from it in several points which I deem of essential importance, instead of using plates of the usual breadth I take them from 4 to 4 $\frac{1}{4}$ inch broad using a diminished number in proportion to the strength obtained from their width, instead of giving a considerable curvature to these plates lengthwise I make them very nearly straight, bending them so much only as I think necessary to allow of their being brought straight or nearly so by the hand which they are to sustain. The box A. for the axle is bolted on to the lower side of the spring as in fig 3. the bolts used being well fitted to hold in the centre line of the plates so as to keep them in their places without the aid of the slot and slot generally employed to check the ends of such springs. Also by avoiding unnecessary thickness in the bearing box bring the journal of the axle as near to the lower side of the spring as can be safely done in order that a thin joining the end bearings of the spring and the axle of the

ngle may approach as nearly as possible to a straight one by this means I almost annihilate the tendency to twist the spring by the lateral pressure of the angle the great width of the spring and its straightness also aid in a very high degree in sustaining it against this pressure. I do not form a scroll or eye on either end of the spring but allow each to pass into a pocket or mortise in the metal bearings B.B. usually of cast iron and bolted to the inner side of the side rail of the car. These pockets need ^{be} no deeper than is necessary to admit the spring as there is scarcely any sensible difference in its length when loaded or not. It therefore sustains the longitudinal thrust without play which is not the case with a curved spring. They also fit it closely in width and thickness and thus check its tendency to twist. The dimensions of these springs must vary according to circumstances but for a car intended to carry 3 tons the following I consider as in good proportion. Length 37 inches breadth 4 inches middle thickness $3\frac{1}{4}$ inches plates in number each one fourth of an inch thick in the middle and excepting the two upper ones tapers towards their ends and diminishing in length in the usual way. The journals of the angle when my spring is used must be made with a button or knob as shown at A. fig 6. This has been generally done when the springs shown in figs 14 & 2. have been employed and is always advantageous as it divides the lateral thrust between the two sides of the car by affording a shoulder on each side of the by B. whilst the spring which I have described as my invention is equally efficient with those shown in figs 14 & 2. and is free from the objections of those of fig. 38 & 4. They can be afforded at about one half the price of the former owing to diminished quantity of the metal used in making them. But more especially to the great saving of labour in their construction from causes which will be obvious to every carpenter-workman. What I claim as my invention is the general construction of the aforesaid spring as resulting from the employment of plates of steel of much greater width than has hitherto been employed for the springs of rail cars and from the making of those plates straight in every part thereby preventing any sensible alteration in their length when in action and admitting of their being both inserted in pockets formed in comparatively light bearing plates making further weight of B. Drawing ^{Fig. 38 & 4.}
